M. C. GUINN

THREAD CONTROLLING MECHANISM FOR SEWING MACHINES

Filed May 12, 1922

UNITED STATES PATENT OFFICE.

MARY C. GUINN, OF DEWAR, OKLAHOMA.

THREAD-CONTROLLING MECHANISM FOR SEWING MACHINES.

Application filed May 12, 1922. Serial No. 560,315.

To all whom it may concern:

Be it known that I, MARY C. GUINN, a citizen of the United States, residing at Dewar, in the county of Okmulgee and State 5 of Oklahoma, have invented certain new and useful Improvements in a Thread-Controlling Mechanism for Sewing Machines; and I do hereby declare the following to be a full, clear, and exact description of the 10 invention, such as will enable others skilled in the art to which it appertains to make and use the same.

My invention relates to a thread controlling mechanism for a sewing machine and 15 has for its primary object the provision of a thread controlling mechanism simple in construction and effective in operation, in which the parts are so constructed and arranged with respect to each other that the thread 20 may be inserted therein with a minimum expenditure of time and effort.

The invention has for another object the provision of a slack thread controlling mechanism in which the parts are arranged 25 to guide and control a plurality of needle threads in a hem stitch sewing machine and other types of sewing machines.

The invention has for a further object the provision of a thread controlling mechanism in the nature of an attachment particularly adapted to be mounted on a sewing machine head.

The invention has for a still further object the provision of a thread controlling mechanism simple in construction and effective in operation for taking up slack in a sewing thread during the operation of the stitch forming mechanism.

With the foregoing and other objects in 40 view the invention consists in the novel construction and arrangement of cooperating parts as hereinafter more specifically described, claimed and shown in the accompanying drawing, in which:—

Figure 1 is a side elevation of a sewing machine head with my thread controlling mechanism applied thereto,

Figure 2 is a side elevation of the thread controlling mechanism in position on the 50 sewing machine head.

Figure 3 is a top plan view of said mechanism with the sewing machine head shown in section,

Figure 4 is a detail section on the line 55 4—4 of Figure 2,

Figure 5 is a detail section on the line 5—5 of Figure 2, and

Figure 6 is a detail section of the upper portion of the frame work on the line 6—6 of Figure 3.

Referring in detail to the sewing machine shown on the drawings 1 indicates the overhanging arm, 2 the head having mounted thereon the thread guides 3, 4 and 5, the spring pressed tension disks 6 and the vertically operable take-up arm 7, all of usual construction.

Secured near the lower end and front edge of the face plate A of the head 2 is the spring arm thread guide attachment, 70 having a horizontally projecting angle-bar 8 provided with a vertically projecting lug 9 and a laterally projecting lug 10 secured to the face plate A by screws 12 and 13 respectively. Projecting downwardly from the angle bar 8 are two spaced, parallel angle bars 14 and 15. The angle bar 14 is secured to the bar 8 by the screw 16 passing through the lugs 17 and 18 on the ends of vertically and horizontally disposed flanges, 80 respectively, of the angle bar 8. The angle bar 15 is secured to the face plate A by one or more screws 19. Beneath the horizontal flange of the bar 8, and connecting the upper ends of bars 14 and 15 by means of screws 85 20 and 21 is the horizontal bar 22. Between the bars 14 and 15 and spaced therefrom are two vertical bars 23 and 24 having along their outer edges inclined thread engaging surfaces 23' and 24' respectively 90 and at their lower ends lugs 25 and 26, respectively, secured by a screw 27 on the opposite sides of the rearwardly and upwardly projecting arm 28. This arm has disposed on opposite sides thereof and spaced therefrom and secured thereto by screw 29, two forwardly and upwardly projecting arms 30 and 31 having at their upper ends laterally projecting lugs 32 and 33 respectively. As shown in Figure 5 the screw 20 passes 95 through lug 32 and secures the same to bar 23 angle bar 14 and horizontal bar 22. A screw 21 passes through lug 33 and secures the same to bar 24, angle bar 15 and bar 22.

Mounted on the screw 29 and on opposite sides of the arm 28 are coiled springs 34 and 35. As shown in Figure 3 the spring 34, has one end secured in bar 30, and has its opposite end formed into a long arm 36 110

- projecting through the opening between bars 23 and 24. The free end of the arm 36 terminates in a thread engaging hook 37. The spring 35 which is similar to 5 spring 34 has one end secured in bar 31 and has its opposite end formed into a long arm projecting through the opening between the bars 23 and 24 and terminating in a thread engaging hook 39.
- 10 The sewing threads pass through the guides 3 and 4, tension device 6, the thread engaging hooks 37 and 39, the take-up 7 and guides 5 to the needles of the sewing machine. One sewing thread 40 passes between the bars 14 and 23 and is controlled and guided by the walls thereof during the up and down movement of the guide 37 in taking up the slack of the thread during the stitch forming operation (see Figure 4).
- 15 20 The other thread 41 passes between the bars 15 and 24 and is controlled and guided by the walls thereof during the up and down movement of the thread guide 38 in taking up slack in the thread during the stitch forming operation. Each of the threads 25 may be quickly inserted in its proper position in the slack thread controlling device without the operator at any time disengaging the threads. For instance to place the 30 thread in hook 39 all that is necessary is to draw the thread below the attachment then upwardly into the open-ended space between the vertically extending members 15 and 24 and thence into the hook 39.
- 35 40 While a preferred embodiment of the invention has been shown and described it will be understood that minor changes in the details of construction and arrangement of parts may be resorted to within the scope 45 of what is claimed without departing from the spirit of the invention.

Having thus described the invention, what I claim is:—

1. In a device of the class described, a 45 plurality of spring arms, a supporting arm between said spring arms, other supporting arms angularly disposed to said first mentioned supporting arm and on opposite sides of said spring arms, means for uniting the 50 corresponding ends of said arms, a frame for uniting the corresponding opposite ends of said supporting arms, said spring arms being secured at the first mentioned corresponding ends, said spring arms having free 55 ends projecting through said frame, and thread guiding hooks on said free ends.

2. A thread controlling mechanism consisting of a frame, the frame including a 60 depending bar, means cooperating with the bar to provide a thread guide opening, an arm extending rearwardly from the bar, an arm extending forwardly from the first arm to the frame and terminating above said opening, and a thread guiding hook disposed

adjacent said first arm to engage the thread 65 adjacent said opening.

3. A thread controlling mechanism consisting of a frame; the frame including a depending bar, means cooperating with the bar to provide a thread guide opening, an arm 70 extending rearwardly from the bar, an arm extending forwardly from the first arm to the frame and terminating above said opening, means connecting said arms together, and a thread guiding hook mounted by said means 75 and operatively disposed adjacent said opening.

4. A thread controlling mechanism consisting of a laterally disposed attaching bar, 80 a bar depending therefrom and having a forwardly extending lug adjacent its lower end, a bar spaced from the second bar and depending from the first bar to provide a thread guide opening between the second and third bars, a rearwardly extending arm 85 secured to said lug, a rearwardly extending arm secured to the first bar, means securing said arms together, and a thread guiding hook positioned by said means and operatively disposed adjacent said opening. 90

5. A thread controlling mechanism consisting of a laterally disposed attaching bar, a bar depending therefrom and having a forwardly extending lug adjacent its lower end, a bar spaced from the second bar and depending from the first bar to provide a thread guide opening between the second and third bars, a rearwardly extending arm 95 secured to said lug, a rearwardly extending arm secured to the first bar, means securing said arms together, a thread guiding hook carried by the frame and operatively disposed adjacent said opening, and said thread guiding hook being resilient and having a coil surrounding said means and secured to 100 one of said arms. 105

6. A thread controlling mechanism consisting of a laterally disposed attaching bar, bars depending from said bar, a rearwardly extending arm secured to the second mentioned bars, bars depending from the first mentioned bar in spaced relation to the second mentioned bars to provide thread-guide openings, downwardly and rearwardly extending arms connected to the first mentioned bar, means connecting the arms together, coil springs surrounding said means and attached at one end to the second mentioned arms, and hook arms extending from said springs and being operatively disposed 110 adjacent said openings for engagement with the thread. 115

In testimony whereof I affix my signature in presence of two witnesses.

MARY C. GUINN.
